UNITED STATES PATENT OFFICE.

JOHN STRATTON, OF ALTRINCHAM, AND ERNEST ALEXANDER CLAREMONT, OF OLD TRAFFORD, MANCHESTER, ENGLAND.

APPARATUS FOR DRAWING WIRE.

1,015,913.

Specification of Letters Patent.

Patented Jan. 30, 1912.

Application filed January 4, 1910. Serial No. 536,430.

To all whom it may concern:

Be it known that we, JOHN STRATTON and ERNEST ALEXANDER CLAREMONT, subjects of the King of Great Britain, and residing, respectively, at Altrincham, county of Chester, and at Old Trafford, Manchester, county of Lancaster, England, have made certain new and useful Inventions Relating to Apparatus for Drawing Wire, of which the following is a specification.

This invention relates to the type of wire drawing apparatus, in which as described in our United States Patent No. 931,971, of August 24, 1909, relating thereto the die holder supporting the solid die may comprise a coöperating plug and cap which may have any suitable provision, such as a screw connection of any description between them to powerfully force the die portion or point into an aperture or compressing funnel and thus compress to the desired gage the constricted throat of the die which according to regular practice is located adjacent the discharge end of the die that is in the compressing aperture.

This present invention relates especially to wire drawing apparatus of this type in which the compressing funnel is preferably given a greater angle than the portion of the die or die point which is brought into engagement therewith to promote the localized compression of the discharge end or throat of the die, the die end being if desired of reduced substantially uniform section for a considerable distance adjacent its end, so that it can be forced for a considerable distance into engagement with the compressing funnel so as to successively compress different portions of the die end and reduce the gage of the throat before it is necessary to remove and reshape the die end to insure its proper coöperation with the compressing funnel; also if desired the die may be held in alinement with the coöperating compressing funnel in the cap or die holder member by forming suitable coöperating guiding members on the cap and die, thus minimizing lateral distortion of the die during its compression.

In the accompanying drawings showing in a somewhat diagrammatic way illustra-

tive embodiments of this invention, Figure 1 is a longitudinal section of one form of apparatus. Figs. 2, 3 and 4 are similar sectional views of modified constructions.

55

In this apparatus the die holder supporting the die may comprise a plurality of members, one of which may be formed with a suitable aperture or compressing funnel with which the die end or point adjacent the throat may coöperate. The die holder members may be provided, for example, with a screw connection of any desired description so as to powerfully force the die end into the compressing funnel to the desired extent 60 to reduce the gage of the die throat as desired. For example, in the illustrative embodiment of the invention shown in Fig. 1, the cap 8 may be provided with a compressing funnel 18 and the plug 9 may have 65 any desired form of screw connection with the cap to force the end of the die 1 into the compressing funnel. The plug may be provided with an external screw thread 14 co-operating with an internal thread 15 on the 70 cap which may have a polygonal or other non-circular form of exterior so that the relative rotation of the parts may be readily effected, the plug being preferably provided with a suitable polygonal nut 11 for this 75 purpose.

The die 1 may if desired be formed with a gradually contracting aperture terminating in the discharge throat 2 and with a tapered die point 3, preferably of less angle 85 than the coöperating compressing funnel 18 so that the extreme end of the die point is first brought into engagement with the funnel and wedged inward, definitely localizing the compression of the plastic or 90 yieldable steel die and reducing its throat 2 to the desired extent. The die may also be formed with a reduced section of considerable length adjacent its point so that it is possible to force the die into the compressing funnel for a considerable distance 95 and effect a great many reductions in the gage of the throat by the successive compression of the die end before it becomes necessary to remove and turn or otherwise 100 reshape the die end to insure its proper operation. The die end may, for example,

be formed with a long prismatic or preferably cylindrical reduced die body 4 which is of sufficiently small cross-section to allow the compressing funnel to exert the desired 5 localized wedging or compressing action upon it. Suitable guiding members are preferably provided on the die and cap, such for example, as the guide flange 5 which may be formed on the head or rear 10 portion 6 of the die so as to coöperate with the guide hole 16 in the cap and maintain the die in axial alinement at it is forced forward. Also by forming the die body 4 of the prismatic or cylindrical contour indicated, it may be brought into sufficiently 15 close engagement with the coöperating guide passage 17 to maintain the die in alinement in this way, although of course it is not necessary in all cases to provide 20 these two sets of coöperating guiding members on the die and cap or die holding member formed with the aperture or compressing funnel. The plug which may have the mouth 10 and gradually contracting axial 25 passage through which the wire is drawn in operation may also be provided with a suitable follower 12 to engage the die head 6 and force the die point forward as indicated.

30 In the modified construction shown in Fig. 2, the cap 8 may as indicated be formed with the conical compressing funnel 18 with which the end of the die 1 may be forced into engagement by the coöperating plug 9. The die may as indicated in this instance 35 be held in alinement by suitable guiding members formed on the die and plug in which a suitable seat or shallow hole 13 may be formed to coöperate 40 with a suitable guide flange 5 on the die head 6. The die may in this instance be formed with the usual slightly tapering axial passage terminating in the throat 2 and may be formed adjacent its forward end 45 with a reduced section in the form of a tapered or substantially conical point, preferably having a less angle than the tapered compressing funnel so as to effect a definitely localized compression as the die point 50 is forced forward. A number of successive reductions in the gage of the throat may be made in this way before it becomes necessary to take the die from the holder and remove the surplus metal from the thickened 55 charge end of the die by turning down its exterior to the desired extent.

It is not necessary in all cases to form the die with a tapered point, since the die may be formed with a substantially prismatic or 60 cylindrical reduced section at the point which is originally forced into engagement with the compressing funnel. Such a construction is illustrated in Fig. 3 in which the cap 8 is shown as provided with the 65 tapered or cylindrical compressing funnel

18 while the die 1 may be formed with a reduced section die body 4 which may be cylindrical at the discharge end 7 when first forced into engagement with the compressing funnel, so that there is the desired difference of angle between the compressing funnel and the cylindrical reduced body of the die which may if desired be adjacent its discharge end. It is, of course, understood that the inward wedging of the die end by 70 the funnel successively reduces the constricted discharge throat 2 of the die and simultaneously gives that part of the die end which has been forced against the compressing funnel a corresponding tapered or 75 conical form. In this instance the alinement of the die with respect to the holder may be effected by forming the cap with a suitable guide passage 17 with which the cylindrical body 4 may coöperate to give 80 a suitable guiding or alining action and also if desired suitable guide members or a continuous guide flange 5 may be formed on the die as indicated in dotted lines to coöperate with a correspondingly shaped 85 guide hole 16 in the cap as the die is pressed forward by the engagement between the die head 6 and the follower 12 on the plug 9. If desired, however, the guiding means may merely comprise a suitable guide flange ad- 90 jacent the rear end or head of the die and a coöperating guide hole or seat in one of the die holder members. As is shown in Fig. 4, the die 1 may be provided with a 95 guide flange 5 adjacent its rear end coöperating with a guide hole 16 shown in this 100 instance as formed on the cap 8, although of course this is not necessary in all cases. In this instance the die may be initially provided with the tapered die point 3 which 105 may as indicated have substantially the same angle as the compressing funnel 18 in the cap and the die may have the reduced cylindrical die body 4 adjacent its discharge end so as to allow a considerable amount of suc- 110 cessive compression and regaging of its throat 2 before other reshaping is necessary. It will be understood that by forming the guiding alining members adjacent the die head or rear of the die the forward portion of the die is left free and objectionable sticking or cramping in the die holder 115 minimized.

Having described this invention in connection with a number of illustrative embodiments, forms, proportions and arrangements of parts, to the details of which disclosure the invention is not of course to be limited, what is claimed as new and what is desired to be secured by Letters Patent is 125 set forth in the appended claims, which in some cases broadly cover a form of construction in which the die may be formed integrally with or permanently attached to one of the members of the die holder, as is 130

illustrated in our copending application, 536,431, filed January 4, 1910, which specifically claims this construction.

We claim—

5. 1. In wire drawing apparatus, a die holder comprising a cap provided with a compressing funnel and a coöperating plug having screw connection with said cap, a die supported by said die holder and having a 10 cylindrical reduced die body adjacent its discharge end, having a slightly tapering aperture provided with a constricted throat adjacent its discharge end and having a tapered die point coöperating with said 15 compressing funnel and having a less angle than said funnel to bring the outer portion of said tapered die point first into engagement with said funnel when said die is forced forward and its throat contracted by 20 the relative compressing movement between said cap and plug, coöperating guiding members formed on said cap and die to maintain them in alinement, said guiding members comprising a guide flange adjacent the 25 rear end of said die and a coöperating guide-hole in said cap and a guiding passage in said cap coöperating with said reduced die body. 2. In wire drawing apparatus, a die 30 holder comprising a cap provided with a compressing funnel and a coöperating plug, a die supported by said die holder and having a substantially uniform reduced section die body adjacent its discharge end, having 35 an aperture provided with a constricted throat adjacent the discharge end of the die and having a tapered die point of less angle than said funnel and coöperating therewith at its outer end and coöperating guiding 40 members formed on said cap and die to maintain them in alinement. 3. In wire drawing apparatus, a die 45 holder comprising a cap provided with a compressing funnel and a coöperating plug, a die supported by said die holder and having a substantially uniform reduced section die body adjacent its discharge end and having a tapered die point at its discharge end for coöperation with said compressing 50 funnel to contract the die throat by the relative compressing movement between said cap and plug and guiding members formed on said cap and die to maintain them in alinement. 4. In wire drawing apparatus, a die 55 holder comprising a plurality of coöperating members, having means to cause a compressing movement between them, one of said members being formed with a compressing 60 funnel, a die supported by said die holder and having a substantially uniform reduced section die body adjacent its discharge end and having a tapered die point coöperating with said compressing funnel and formed 65 during the compressing movement of said die holder and guiding means to maintain said die in alinement with said compressing funnel. 5. In wire drawing apparatus, a die 70 holder comprising a plurality of coöperating members, having means to cause a compressing movement between them, one of said members being provided with a compressing funnel, a die supported by said die holder and having a substantially uniform reduced section end coöperating with said compressing funnel to contract the throat in said die end on the compressing movement of said die holder and guiding means to maintain said die and funnel in alinement. 6. In wire drawing apparatus, a die 75 holder comprising a plurality of coöperating members, having means to cause a compressing movement between them, one of said members being provided with a compressing funnel, a die supported by said die holder and having a tapered die point coöperating with said compressing funnel and having a less angle than said funnel to bring the outer portion of said die point first into engagement with said funnel during the compressing movement of said die holder and means to maintain said die in alinement with said funnel. 7. In wire drawing apparatus, a die 80 holder comprising a plurality of coöperating members, having means to cause a compressing movement between them, one of said members being provided with a compressing funnel and a die supported by said die holder and having a reduced section end coöperating with said compressing funnel and having a less angle than said funnel to bring the extreme die end first into engagement with said funnel on the compressing movement of said die holder. 8. In wire drawing apparatus, a die 85 holder comprising a plurality of coöperating members, having means to cause a compressing movement between them, one of said members being provided with a compressing funnel and a die supported by said die holder and having a reduced substantially uniform section portion coöperating with said compressing funnel and adapted to be successively compressed thereby and the die throat contracted by the movement of the die holder. 9. In wire drawing apparatus, a die 90 holder comprising a plurality of coöperating members, having means to cause a compressing movement between them, one of said members being provided with a compressing funnel, a solid die having a constricted throat adjacent its discharge end supported by said die holder and having a tapered reduced discharge end coöperating with said compressing funnel and formed 95 with a less angle than said funnel to bring the outer portion of said die point first into engagement with said funnel during the compressing movement of said die holder. 10. In wire drawing apparatus, a die 100 holder comprising a plurality of coöperating members, having means to cause a compressing movement between them, one of said members being provided with a compressing funnel and a die supported by said die holder and having a reduced substantially uniform section portion coöperating with said compressing funnel and adapted to be successively compressed thereby and the die throat contracted by the movement of the die holder. 11. In wire drawing apparatus, a die 105 holder comprising a plurality of coöperating members, having means to cause a compressing movement between them, one of said members being provided with a compressing funnel and a die supported by said die holder and having a reduced substantially uniform section portion coöperating with said compressing funnel and adapted to be successively compressed thereby and the die throat contracted by the movement of the die holder. 12. In wire drawing apparatus, a die 110 holder comprising a plurality of coöperating members, having means to cause a compressing movement between them, one of said members being provided with a compressing funnel and a die supported by said die holder and having a reduced substantially uniform section portion coöperating with said compressing funnel and adapted to be successively compressed thereby and the die throat contracted by the movement of the die holder. 13. In wire drawing apparatus, a die 115 holder comprising a plurality of coöperating members, having means to cause a compressing movement between them, one of said members being provided with a compressing funnel and a die supported by said die holder and having a reduced substantially uniform section portion coöperating with said compressing funnel and adapted to be successively compressed thereby and the die throat contracted by the movement of the die holder. 14. In wire drawing apparatus, a die 120 holder comprising a plurality of coöperating members, having means to cause a compressing movement between them, one of said members being provided with a compressing funnel, a solid die having a constricted throat adjacent its discharge end supported by said die holder and having a tapered reduced discharge end coöperating with said compressing funnel and formed 125 with a less angle than said funnel to bring the outer portion of said die point first into engagement with said funnel during the compressing movement of said die holder. 15. In wire drawing apparatus, a die 130 holder comprising a plurality of coöperating members, having means to cause a compressing movement between them, one of said members being provided with a compressing funnel, a solid die having a constricted throat adjacent its discharge end supported by said die holder and having a tapered reduced discharge end coöperating with said compressing funnel and formed with a less angle than said funnel to bring the outer portion of said die point first into engagement with said funnel during the compressing movement of said die holder.

the outer portion of said tapered end first into engagement with said funnel by the compressing movement of said die holder.

10. In wire drawing apparatus, a die holder comprising a plurality of coöperating members, having means to cause a compressing movement between them, one of said members being provided with a compressing funnel, a die supported by said die holder and having a reduced section tapered die point coöperating with said compressing funnel and having a less angle than said funnel to bring the outer portion of said tapered die point first into engagement with said funnel and contract the throat in said die point on the compressing movement of said die holder and guiding means to maintain the alinement between said die and compressing funnel.
20. 11. In wire drawing apparatus, a die holder comprising a plurality of coöperating members, having means to cause a compressing movement between them, one of said members being provided with a compressing funnel, a die supported by said die holder and having a reduced substantially uniform section portion coöperating with said compressing funnel and adapted to be successively locally compressed thereby and the corresponding die throat contracted by the movement of the die holder and guiding means to hold said die in alinement with said funnel.
25. 12. In wire drawing apparatus, a die holder comprising a plurality of coöperating members, having means to cause a compressing movement between them, one of said members being provided with a compressing funnel, a die supported by said die holder and having a reduced section portion coöperating with said compressing funnel and having a less angle than said funnel to successively locally compress said reduced section and contract the corresponding die throat by the compressing movement of the die holder and guiding means to maintain the alinement between said die and compressing funnel.

35. 13. In wire drawing apparatus, a die holder comprising a cap provided with a compressing funnel and a coöperating plug, a die supported by said die holder and having a substantially uniform reduced section die body coöperating with said compressing funnel to successively compress a portion of said die body engaging said funnel and contract the corresponding die throat and guiding members formed on said cap and die to maintain them in alinement.
40. 14. In wire drawing apparatus, a die holder comprising a cap provided with a compressing funnel and a coöperating plug, a separate die having a constricted throat adjacent its discharge end supported by said die holder and having a reduced section taper-

ing die point adjacent its discharge end coöperating with said compressing funnel to successively locally compress said die body and correspondingly contract the throat of the die on the compressing movement of said die holder and coöperating guiding members formed on said cap and on said die adjacent the rear end thereof to maintain said die in alinement with said compressing funnel.

70. 15. In wire drawing apparatus, a die holder comprising a plurality of coöperating members, having means to cause a compressing movement between them, one of said members being provided with a compressing funnel and with a guide and a die supported by said die holder and having a reduced section portion coöperating with said compressing funnel and guiding means on said die coöperating with said guide on said member.

75. 16. In wire drawing apparatus, a die holder comprising a cap provided with a compressing funnel and a coöperating plug, a die having a constricted throat adjacent its discharge end supported by said die holder and having a substantially uniform reduced section die body adjacent its discharge end coöperating with said compressing funnel to successively locally compress said die body and correspondingly contract the throat of the die on the compressing movement of said die holder and coöperating guiding members formed on said cap and die to maintain them in alinement.

80. 17. In wire drawing apparatus, a die holder comprising a cap provided with a compressing funnel and a coöperating plug, a die having a constricted throat adjacent its discharge end supported by said die holder and having a reduced section die point coöperating with said compressing funnel and having a less angle than said funnel to bring the outer portion of said die point first into engagement with said funnel during the compressing movement of said die holder and guiding means on said cap and die to maintain them in alinement.

85. 18. In wire drawing apparatus, a die holder comprising a plurality of coöperating members, having means to cause a compressing movement between them, one of said members being provided with a compressing funnel, a die supported by said die holder and having a reduced substantially uniform section portion coöperating with said compressing funnel and adapted to be successively locally compressed thereby and the corresponding die throat contracted by the movement of the members constituting said die holder.

90. 19. In wire drawing apparatus, a die holder comprising a plurality of coöperating members, having means to cause a com-
